(57) **CLAIM**

The ornamental design for a carafe, as shown and described.

DESCRIPTION

FIG. 1 is a perspective view of a carafe with the lid removed for ease of illustration showing my new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof; and

FIG. 8 is a perspective view of carafe with the lid on the carafe of FIG. 1;

FIG. 9 is a perspective view of carafe with the lid removed for ease of illustration showing a second embodiment of our new design;

FIG. 10 is a front view thereof;

FIG. 11 is a rear view thereof;

FIG. 12 is a right side view thereof;

FIG. 13 is a left side view thereof;

FIG. 14 is a top view thereof;

FIG. 15 is a bottom view thereof; and,

FIG. 16 is a perspective view of carafe with the lid on the carafe of FIG. 9.

The broken lines in the drawing depict portions of the carafe that form no part of the claimed design.

1 Claim, 16 Drawing Sheets
